United States Patent Office

Des. 208,990
Patented Oct. 24, 1967

208,990

GARDEN KNIFE

Howard A. Anderson, Pittsburgh, Pa., and Henry J. Rosendall, Grand Rapids, Mich., assignors to Bissell Inc., Grand Rapids, Mich., a corporation of Michigan

Filed Aug. 24, 1966, Ser. No. 3,570

Term of patent 14 years

(Cl. D35—2)

FIG. 1.

FIG. 2.

FIG. 3.

FIGURE 1 is a side elevation of a garden knife, showing our new design, the opposite side being a mirror image; FIG. 2 is a top plan view thereof; and

FIG. 3 is an end view thereof, taken on line 3—3 of FIGURE 1.

We claim:

The ornamental design for a garden knife, substantially as shown and described.
